UNITED STATES PATENT OFFICE.

SAMUEL C. SHAFFNER, OF CHICAGO, ILLINOIS.

TROUSERS-FORM.

1,366,505.

Specification of Letters Patent. Patented Jan. 25, 1921.

Application filed April 7, 1919. Serial No. 287,937.

To all whom it may concern:

Be it known that I, SAMUEL C. SHAFFNER, a citizen of the United States, residing at Chicago, in the county of Cook and State of Illinois, have invented a certain new and useful Improvement in Trousers-Forms, of which the following is a specification.

My invention relates to an improved trousers form in which the form consists of two pieces of relatively thin material secured together by means of spring structures of one kind or another adapted to force the two parts of the structure apart when placed in the leg of a trousers so as to remove the wrinkles and restore the trousers leg to its desired pressed condition. By my invention I provide the outer edges of the parts of the form with a conformation of the same kind as originally given to the trousers so that the pressing operation not only removes the wrinkles from the cloth but also shapes the trousers leg to the exact shape that it was given when made, and as a result a much improved appearance is presented over that resulting from the use of ordinary trousers forms with straight edges. A further feature of improvement of my invention consists of making the edges of the two parts of the form relatively thin so that as a result of the pressing operation the opposite front and rear edges of the trousers leg are creased as though they had been pressed by a tailor.

Using my improved trousers form the edges of trousers leg may either be pressed by means of a warm iron, or the cloth may be dampened and left for a considerable time on the form, as a result of which the form itself will eliminate the wrinkles previously found in the trousers leg and also impart a creased condition to the front and rear edges of the trousers leg in its folded condition.

My invention will best be understood by reference to the accompanying drawings, showing preferred embodiments thereof, in which—

Figure 1 shows in plan view a preferred form of my improved device consisting of two flat pieces, preferably of wood, secured together by wire springs, said springs being in their contracted condition as shown in this figure,

Fig. 2 shows in a view similar to Fig. 1 the form construction shown in said figure in

place inside of a trousers leg with the springs released to form the said trousers leg,

Fig. 3 shows in a view similar to Fig. 1 a modified construction of the structure in which the two parts may be collapsed so as to make the structure more convenient for packing in a suit case,

Fig. 4 is a sectional view of the part shown in Fig. 3 taken along the line of 4—4,

Fig. 5 is a sectional view of the parts shown in Fig. 2 taken along the line 5—5, and

Fig. 6 shows in a view similar to Fig. 1 a modified construction of the form in which cam surfaces are provided on the parts of the form to be actuated by springs connected with an intermediate member.

Similar numerals refer to similar parts throughout the several views.

As shown in Figs. 1 and 2, my improved form consists of two parts, 10 and 11, having their outer edges shaped to conform with the natural shape of the trousers leg as indicated at 12 and 13. These parts are connected together by two pairs of springs 80 made from wire as shown at 14 and 15, one spring of each pair being on one side of parts 10 and 11, while the other spring is on the other side and in similar position. Said pairs of springs are tied together as 85 indicated at 16 and 17 to hold the springs in flat position against the surfaces of the parts 10 and 11. Hooks 19 are provided at one end of the form and a hook 18 is provided at the other end thereof to hold 90 the parts of the form together with the springs 14 and 15 in contracted condition when it is desired to insert the form in the leg of a pair of trousers. The outer edges of the parts 10 and 11 are preferably chamfered as indicated at 20 and 21 so as to present relatively sharp edges to the goods at the places where they are folded in forming the trousers, so as to crease the front and rear portions of the trousers in much the 100 way that they are usually creased by the pressing operation at the tailors.

Since the parts of the form are flat, if it is so desired a warm or hot iron may be used to press out the wrinkles which are most 105 numerous at the knee of the trousers leg and the iron may also be used to make the creases in the front and rear portions of the trousers. Instead of using the iron, however, if it is not necessary to press the trousers 110

quickly they may be dampened and left with the structure inside the leg for a time which will result in completely removing the wrinkles and making good creases in 5 both the front and rear portion of the trousers leg.

In using the form shown in Figs. 1 and 2 the hooks 18 and 19 are placed in the position shown in Fig. 1, the structure is then 10 inserted in the leg of the trousers and when it is in proper position the hook 18 is removed and the hooks 19 are separated from each other which permits the springs 14 and 15 to move the parts 10 and 11 away from 15 each other to exert a forming action on the cloth of the trousers leg. Similarly when it is desired to remove the form from the pressed trousers leg the hooks may again be placed in the position shown in Fig. 1 and 20 the form readily removed from the trousers.

In the construction shown in Fig. 3 the parts 22 and 23 together constitute one portion of the form corresponding with the portion 10 shown in Fig. 1, and the parts 24 and 25 together constitute the other part of the form corresponding with the part 11 shown in Fig. 1. The parts 22 and 24 have projecting from them extensions 26 and 27 slightly offset from the plane of the parts 30 22 and 24 to overlap the parts 23 and 25 respectively, so that the main parts of the form are in the same plane. The offset extensions 26 and 27 are provided with elongated slots 28 and 29 for receiving the enlarged heads of the studs 30 and 31 carried by the parts 23 and 25 to secure said parts rigidly to the parts 22 and 24 when the form is in use. Spring links, 32, 33 and 34, 35 are pivotally connected together as 40 shown at 36 and 37 and these links are pivotally connected to the parts of the form so that when they occupy the position shown in full lines the form is in its collapsed condition and when they are removed to the 45 position shown in dotted lines the form is in its expanded condition.

With this construction which may be of sheet metal if desired the edges are conformed as described above in connection 50 with Fig. 1 and for the same purposes.

In the construction shown in Fig. 6, the parts 38 and 39 of the form are provided on their inner edges with cam surfaces 40, 41 and 42, 43 engaged by the springs 44 and 55 45 carried by a central operating rod 46. The springs 44 and 45 are preferably provided at their outer ends with bent ears as indicated for retaining said springs in engagement with said cam surfaces. As a result of this construction when the operating 60 rod 46 is in the position shown in Fig. 6 the pressure upon the springs 44 and 45 is relatively light and the parts 38 and 39 are in their collapsed position. After the structure 65 has been inserted in the leg of trousers

the rod 46 is pulled outwardly by means of the knob on its right hand end as shown in Fig. 6 and the springs 43 and 44 moving along the cam surfaces separate the parts 38 and 39 with increasing spring pressure 70 depending upon the distance to which the rod 36 is moved outwardly. The edges of the parts 38 and 39 are preferably conformed in the same manner as described above for the edges of the parts 10 and 11 in connection with Fig. 1 for the same purposes. 75

While I have shown my invention in the particular embodiments above described, I do not however limit myself to these exact constructions as I may employ equivalents 80 thereof known to the art at the time of the filing of this application without departing from the scope of the appended claims; for example, the parts 22, 23 and 24, 25 may be respectively hinged together instead of using 85 the construction above described for connecting them together.

What I claim is:

1. In a trousers form, the combination of 90 two flat members having outer edges conformed to the shape of a trousers leg, each of said members having holes through it to serve as pivot bearings, and springs having bent pivot ends extending through said holes to hold said members apart, whereby movement of said members toward or away from each other rotates said pivot ends in said holes.

2. In a trousers form, the combination of 100 two flat members having outer edges conformed to the shape of a trousers leg, each of said members having two holes through it to serve as pivot bearings, a pair of similarly shaped wire springs at each end of said members, one on each side of said members 105 and having bent pivot ends extending through one hole in each member, the springs of each pair extending in the same direction, and a tie between said members engaging the mid-portions of the springs 110 of each pair to hold them parallel with said members.

3. In a trousers form, the combination of 115 two flat members having outer edges conformed to the shape of a trousers leg, each of said members having holes through it to serve as pivot bearings, springs having bent pivot ends extending through said holes to hold said members apart, whereby movement of said members toward or away from each other rotates said pivot ends in said holes, and hooks extending through said holes and secured therein for holding said members together against the action of said springs when desired. 120

4. In a trousers form, the combination of 125 two flat members having outer edges conformed to the shape of a trousers leg, each of said members having holes through it to serve as pivot bearings, springs having bent 130

pivot ends extending through said holes to hold said members apart, whereby movement of said members toward or away from each other rotates said pivot ends in said holes, the smaller ends of said members being of reduced width to provide gripping surfaces for the thumb and forefinger, and means

for engaging said reduced portions to hold said smaller ends against the action of said springs.

10

In witness whereof, I hereunto subscribe my name this 3rd day of April A. D., 1919.

SAMUEL C. SHAFFNER.
